FIG. 2

INVENTOR
Euell I. La Chapelle.
By Richard P. Elliott,
Attorney.

UNITED STATES PATENT OFFICE.

EUCLID I. LA CHAPELLE, OF BEVERLY, MASSACHUSETTS.

MACHINE FOR TURNING AND RELASTING SHOES.

1,132,479.

Specification of Letters Patent. Patented Mar. 16, 1915.

Application filed April 5, 1912. Serial No. 688,598.

To all whom it may concern:

Be it known that I, EUCLID I. LA CHAPELLE, a citizen of the United States, residing in Beverly, county of Essex, Commonwealth of Massachusetts, have invented certain new and useful Improvements in Machines for Turning and Relasting Shoes, of which the following is a specification, reference being had to the drawings accompanying the same and forming a part thereof.

My invention relates to improvements in machines for turning the uppers upon the sole of what are termed turn shoes, and for relasting the shoe.

The objects of my invention are as follows:—To so arrange a turning and relasting mechanism that the more laborious portions of the work may be accomplished by the foot of the operator; to so arrange the mechanism that the same operating parts of the device may be used for both operations; and further to provide means to assist the operator in drawing the fore part of the shoe upon the forepart of the last in the operation of relasting, and to provide a vent to the toe of the shoe so that the air confined therein may easily escape.

In the drawings which accompany this specification—Figure 1 shows a front elevation of the machine with the clamping device closed, and a last in the relasting portion of the machine, and a shoe partially relasted; Fig. 2 is a side sectional elevation of the machine showing the parts in the same position as they are in Fig. 1; Fig. 3 shows a portion of the upper part of the machine comprising the clamping portions with the coöperating clamping portion open; Fig. 4 is a sectional view looking downward upon the machine taken at line 4—4, Fig. 2, but with the last and shoe removed.

In the drawings illustrating my device, 1 represents the bearing portion designed to support the machine by being fastened to a bench or other supporting means. A tube 2 is secured in the bearing portion and extends downwardly to the floor and has secured upon its lower end the base-plate 3. There is secured in the upper portion of the tube 2 a rod 4 which extends upwardly and has pivoted in its upper end a roller 5. A sleeve 6 is slidably mounted upon the rod 4 near its upper end and has formed upon it the clamping-member 7. There is secured 55 to the sleeve 6 the coöperating clamping member 8 having the clamping surface 9

formed upon its free end. At the inner ends of the clamping-member 8 there are formed circular slots 10 designed to be mounted upon the bearing screws 11, 11, in such way 60 that the coöperating clamp 8 will move the length of the slot upon the bearing-screws 11, 11, when the clamping surface 9 is moved to clamp the sole of a shoe between it and the clamping surface 7. The sleeve 6 is held 65 in its uppermost position by means of a compressible spring 12 which is mounted upon the rod 4, and bears at its lower end upon the adjustable collar 13, the collar being adjustably secured by means of a set screw 14. 70 The spiral spring 12 is of sufficient tension to hold the sleeve 6 in its uppermost position.

There is extending downwardly from the inner end of the coöperating clamp 8 a bracket 15 to which there is secured two adjustable rods 16, 16, by means of the screws 15^a, 15^a, which rods extend downwardly and are fastened by suitable means to the treadle portion 17. The treadle portion 17 is moved downwardly by means of the outwardly extending portion 18 arranged to be operated by the foot of the operator.

The sleeve 6 is provided with a locking device to prevent its movement during the major part of the movement of the coöperating clamp 8. This locking device consists of the pivoted bell-crank-lever 19 which is pivoted to the sleeve 6 by means of the pivot 20 and has a locking-bolt 21 pivoted to it, which locking-bolt is of sufficient length to 85 extend through the wall of the sleeve 6 and into the recess 22 formed in the upper end of the rod 4. The bell-crank-lever 19 is provided with a recess 23 to receive the lever 24. The lever 24 is pivoted at the point 25 90 upon the sleeve 6.

Extending crosswise from the lever 24 is a rod 26, shown in Fig. 1, having its ends projecting outwardly so that the ends of the projecting parts 27, 27, will contact with 100 them when the clamping member 8 has been moved to the position shown in Fig. 2, and thereby cause the upper end of the lever 24 to contact with the lever 19 and withdraw the locking-bolt 21.

The two adjustable rods 16, 16, are provided with adjustable sleeves 28 and adjusting screws 29, 29, for the purpose of adjusting the amount of throw of the clamping-members 6 and 8. The weight of the clamping members 6 and 8, and of the other slideable portions of the mechanism are counter-

balanced by means of the weight 30 which is arranged to freely slide up and down inside of the tube 2. The weight 30 is attached to the treadle 17 by means of the fastening screw 31 and the cord 32 which runs over a pulley 33 secured near the upper end of the tube 2.

The relasting portion of the mechanism consists of a tube 34 mounted in the bracket 35 of the bearing portion 1. The tube 34 is open at its upper end and is adapted to receive the socket 36 which is adapted to receive the heel of the last while the shoe is being relasted. The socket 36 is provided with two adjusting studs 37, 37, which may be adjusted in and out in the slots 38, 38, to enable the setting of the last toward or away from the machine. The socket 36 is mounted upon the upper end of the tube 34. This socket 36 is made of flexible steel so that its upper ends will enter the notches 39 formed in the saddle portion 40. By this method of fastening, the socket 36 may be sprung in or out to different widths between the upright portions to accommodate lasts having different widths of heel portions. There is mounted upon the upper end of the tube 34 a sliding-block 41 which is fitted to slide up and down freely on said rod 34. The sliding-block 41 is counterbalanced by means of the weight 42 secured to it by the cord 43 which runs over a suitable pulley in the upper end of the tube 34. The block 41 is provided with five flat flexible springs 44, 44, etc. These springs are flat quite thin and flexible so that they may be bent in to substantially conform to the shape of the fore part of a last, as shown in Fig. 1. The purpose of these springs will be more fully described hereafter.

There is mounted in the block 41 a spring-operated catch or pin 45 which is pressed inwardly by means of the lever 46 and the spring 47 operating upon the lever. The bolt 45 is adapted to enter a hole 48 formed in the front of the tube 34 so as to lock the block 41 at the position it assumes when the end of the pin arrives at a point where it will enter the hole 48. The block 41 is moved downward by means of the rod 49 which is attached to the lug 50 extending backward near its bottom portion. The lower end of the rod 49 is secured in the lug 51 formed upon the treadle 17. As the treadle 17 is moved downward it will pull the block 41 down until the pin 45 enters the hole 48. The block 41 may be moved downward still farther by means of the treadle 52 which is fastened to the block 41 by means of the rod 53. The purpose of this further movement of the block 41 will be more fully explained hereafter.

There are three levers pivoted near the clamping portion 9 of the co-operating clamp 8. One of the levers 54 is pivoted so that it

will swing directly backward from the position shown in Fig. 3. It is pivoted at the point 55. The levers 56 and 57 are pivoted at the sides of the rod 58 so that they may be moved laterally on that rod, as well as oscillated upon it. The levers 54, 56 and 57 are kept normally in the position shown in Fig. 3 by the tension of the springs 59, 60 and 61. The purpose of these levers is to break, or assist in bending, the counter at 75 the heel portion where it joins the sole of the shoe. The counter being somewhat stiff it is hard to bend it with the fingers alone, but with the assistance of these levers it can be bent more easily.

To assist the operator in pulling the shoe downwardly upon the last in the operation of relasting, I provide the two friction sliding members 62 and 63. These members are made out of pieces of spring steel so that 85 they will have more or less elasticity, and their inner faces have secured to them pieces of rubber so that they will cling with more or less friction to the sides of the fore part of a shoe and the edges of the sole, and as 90 before stated, assist in drawing the fore part of the shoe downwardly upon the last in the operation of relasting.

The operation of turning and relasting a shoe on the relasting and turning machine 95 is as follows:—In the operation of a turning shoe, the clamping-members are normally in the position shown in Fig. 3. The upper of a shoe which is wrong side out is passed upwardly over the clamping-portion 100 9 so that said clamping portion bears on the sole near the shank and heel portion. The treadle 17 is then operated by moving it downwardly. The first movement of the treadle will immediately swing the clamping-member 9 forward until the sole is clamped between the surfaces 9 and 7 of the co-operating clamping-members. This partially bends the sole of the shoe upwardly over the roller 5. The pin 21 prevents the 110 clamping member 6 from moving downwardly upon the rod 4 until the sole has been partially bent and the heel portion bent or broken over the sole by means of the hand and the levers 54, 56 and 57. After the heel 115 portion is turned the locking-pin 21 is withdrawn from the hole in the rod 4 by means of the levers 19, 24 and projections 27, 27 and the clamping-members 6 and 7 moved down to bend the sole and complete the 120 turning of the fore part of the shoe. A stop 65 is pivoted to the portion 18 to prevent the full movement of the treadle at the first operation and so that the roller 5 will not be pushed violently into the toe of the 125 shoe. When the stop 65 contacts with the plate 3, the operator moves his foot upon the point 66 to swing the stop 65 to a horizontal position when the treadle 17 can be moved to its lowermost position, its 130

ward movement being limited by the rod 67 which is secured in the member 6 and extends downwardly and enters a hole in the top of the tube 2, said rod 67 having mounted upon it a collar 68 which is provided with a set screw, so that the collar may set at any position on the rod 67 and contact with the top of the tube 2 so as to limit the downward movement, as before stated, of the portion 6. When the fore part of a shoe upper is turned to complete the turning of the upper of the shoe upon the sole, the treadle is released and immediately moves upwardly until the clamping members assume the position shown in Fig. 3, their upward movement being accomplished by means of the spring 12 and the counterweight 30.

In the operation of relasting a shoe, the movement of the clamping members 6 and 8 by means of the treadle 17 is used to relast a shoe in the following manner:—When the relasting and clamping members are in the position shown in Fig. 3, the friction-springs 62 and 63 are swung backwardly to the position shown. When in this position the toe of the last is inserted between the springs 44 and moved into the position that the last is shown in Fig. 2, although in Fig. 2 the clamping-member 8 has been moved to a point where the friction-surfaces 62 and 63 are brought in contact with the shoe upper and sole edges; but before this movement of the clamping-member 8, the operator places the last in position, as before described, and with his hands bends the springs 44, etc., inwardly until they assume the position shown in Fig. 1. When in this position the upper of a shoe may be drawn down over the ends of the springs and the fore part of the last until it assumes the position shown in Fig. 2, when the operator places his foot on the portion 18 of the treadle 17 and pushes the treadle downwardly. The first movement of the treadle causes the clamping member 8 to move on the studs 11, 11, and causes the friction springs 62 and 63 to move in the arc of a circle downwardly and toward the top of the last and into the position shown in Fig. 2. Further movement of the treadle draws the spring-block 41 downwardly and moves the friction-springs 62 and 63 downwardly, and by the friction of said springs 62 and 63 and the flat flexible springs 44 inside the shoe, the upper is drawn downwardly upon the last until the toe of the last projects fully into the toe of the upper. When this is accomplished, the block 41 has been moved down to a point where the spring-bolt 45 will enter the hole 48 in the tube 34. Thereupon, the operator removes his foot from the treadle 17 and allows it to move upwardly until the clamping-member 8 and the friction spring members 62 and 63 assume the position shown in Fig. 3. There-

after, the operator places his foot upon the treadle 52 and thereby moves the block 41 down until the springs 44 are withdrawn from between the last and the inside of the upper of the shoe, when the last and shoe 70 may be removed from the machine and the block 41 allowed to move upwardly to its normal position as shown in Fig. 2.

The thin, flat, flexible springs 44 serve a double purpose. They serve to assist in drawing the upper of the shoe upon the last and at the same time they keep the inside of the upper of the shoe away from the last sufficiently to prevent air being retained in the point of the shoe, or in other words they serve as a vent in the toe of the shoe so that air confined therein can easily get out. The springs serve a further purpose, to wit: Ordinarily, in relasting a shoe without interposing anything between the lining of the shoe and the last, the lining will cling to the last and become more or less puckered, so that a thin strip of steel must be inserted between the last and the lining and moved around within the shoe 90 to straighten out the lining. By the use of the springs which I employ, the lining is so held away from the surface of the last that there is not friction enough between them to pucker or displace the lining, thereby saving one of the operations in relasting a shoe.

I do not wish to confine myself to the exact form of the various parts of the turning and relasting mechanism as shown in the drawings, nor in the location of the various parts as shown, as it is obvious that the form and location of the parts may be materially changed without departing from the spirit of my invention.

What I claim is—

1. A turning and relasting machine comprising coöperating clamping members, one of which is mounted upon the other and arranged to move in the arc of a circle; a lever pivoted to one of said coöperating members and arranged to partially rotate thereon; two levers pivoted on the sides of one of said coöperating members and arranged to move laterally to the pivot as well as to partially rotate thereon; and means for operating said coöperating clamping members to clamp the sole of a shoe.

2. A turning and relasting machine comprising the combination of a fixed member 120 for bending the sole of a shoe; coöperating clamping members slideable on the fixed member; means for locking the clamping members to the fixed member, and means to unlock the clamping members from the fixed member.

3. A turning and relasting machine comprising a bearing-rod; a clamping member movably mounted on said bearing-rod; a coöperating clamping member mount-

- ed on said first mentioned clamping member and arranged to move in the arc of a circle thereon; a spring-operated locking-bolt for locking the movable clamping member to the bearing-rod mounted on said first mentioned clamping member; projecting parts secured to said coöperating clamping member arranged to withdraw said locking bolt; and means for operating said clamping members.
4. A turning and relasting machine comprising a bearing-rod; a clamping member movably supported thereon; a spring-operated locking bolt on said clamping member for locking it to the bearing-rod; a spring for holding said clamping member in its normal upward position; a coöperating clamping member mounted on said first mentioned clamping member and arranged to move in the arc of a circle; a treadle for operating both said clamping members; means connecting the treadle with said clamping members; means operated by the treadle for unlocking said locking bolt; and a stop on the treadle for limiting the downward movement of said clamping members, so arranged that the stop can be thrown out of operative position and the clamping members permitted to be moved to their full movement.
5. A turning and relasting machine comprising longitudinally movable coöperative clamping members; means for slightly bending the sole of a shoe during the operation of clamping the sole; and a plurality of levers for bending the heel part of the shoe and turning it on the sole thereof.
6. A turning and relasting machine comprising a last support; elastic means arranged to contact with the outside of the forepart and sole of the shoe for pressing the forepart of the shoe upon the forepart of the last; thin, flat, flexible means arranged between the inside of the shoe and the last for drawing the forepart of the shoe upon the last and a sliding block to which said flexible means are secured; a rod connecting said sliding block with a treadle; a spring-operated locking-bolt mounted on said sliding-block; means for withdrawing said locking-bolt; and a rod and treadle connected with said sliding-block for fully withdrawing said flexible means from between the inside of the shoe and the last.
7. A turning and relasting machine comprising the combination with a clamping and turning device of opposed elastic friction members mounted on one of the clamping members and arranged to move in the arc of a circle and vertically; an adjustable support arranged to receive the heel part of a last; a sliding-block arranged contiguous to said last; flexible members mounted on said sliding-block; means for moving the elastic members into contact with the forepart of a shoe; and means for moving the flexible members longitudinally with relation to the forepart of the last and to withdraw them from the shoe.
8. A turning and relasting machine comprising the combination of friction members to press the fore part of a shoe upon a last; means for operating said friction members so they will engage the sole edge and sides of a shoe vamp; a sliding-block; a plurality of thin, flat, flexible members secured to the sliding-block; a locking-bolt mounted on the sliding-block to prevent vertical movement of said sliding-block; a treadle for initially operating said sliding-block; a second treadle for completing its operation; and means for returning the sliding-block to its normal position.
9. A turning and relasting machine comprising means for relasting the forepart of a shoe, comprising a plurality of thin, flat, flexible strips formed and arranged to bend to conform to the contour of the forepart of a last; and means for moving said flexible strips longitudinally of the last to draw the forepart of the shoe upon a last.
10. A turning and relasting machine, comprising a support for a last; and means for drawing the forepart of a shoe onto the last, arranged so its first movement will be in the arc of a circle to engage the edge of the sole and vamp to bend the sole, and thereafter move longitudinally of the last to draw the forepart of the shoe onto the last.
11. A turning and relasting machine, comprising an adjustable support for a last; means for drawing the forepart of a shoe onto a last, comprising thin, flat flexible strips arranged between the surface of the last and the inside of the shoe; means for moving said flexible strips longitudinally of the last; and means for returning said flexible strips to their normal position.
12. A machine for turning the uppers of shoes and relasting the same, comprising the combination of a fixed member for bending the sole; coöperating clamping members slidably mounted on the fixed member, one of said clamping members mounted upon the other and arranged to move in the arc of a circle; means for locking the clamping members to the fixed member; and means to unlock the clamping members from the fixed member.
- In testimony whereof, I have hereunto set my hand, in the presence of two subscribing witnesses, this the 21st day of March, A. D. 1912.
